CLAIM

The ornamental design for a clamping device, as shown and described.

DESCRIPTION

FIG. 1 is a front elevation view of a clamping device showing our new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, front and left side perspective view thereof;

FIG. 8 is a top, rear and right side perspective view thereof; and,

FIG. 9 is a top, front and left side perspective view thereof in alternative position.

The portions of the design shown in broken lines in FIG. 6 are for the purpose of illustrating the environment only and form no part of the claimed design.
